ASSIGNORS TO HAMILTON-BROWN SHOE COMPANY, OF ST. LOUIS, MISSOURI, A COR-
PORATION OF MISSOURI.

HEEL-SETTING CLAMP.

1,245,732.

Specification of Letters Patent.

Patented Nov. 6, 1917.

Application filed June 6, 1917. Serial No. 173,085.

To all whom it may concern:

Be it known that we, GEORGE W. JULOW, DAVID E. SPATHELF, and EUGENE SEHL, citizens of the United States, residing at the 5 city of St. Louis, in the State of Missouri, have invented certain new and useful Improvements in Heel-Setting Clamps, of which the following is a specification.

The object of this invention is to provide 10 an efficient and factory-like means for setting the heels of shoes in conjunction with the rest of the shoe, and may be utilized whether the heels are made of wood or other material and whether or not they are 15 of the kind commonly called French heels.

In the accompanying drawings forming part of this specification and in which like numbers of reference denote like parts wherever they occur,

20 Figure 1 is a side elevation;

Fig. 2 is a side elevation of a shoe with the heel disjoined;

Fig. 3 is a side elevation of such shoe 25 after the heel has been attached thereto by nailing and with glue, said shoe containing a last and being supported ready for clamping for setting purposes;

Fig. 4 is a view similar to Fig. 3, but 30 showing the clamp applied, the shoe shown in side elevation in this figure being in the same relation to other parts as the shoe shown on a smaller scale in rear elevation at the left of Fig. 1; and

Fig. 5 is a detail view of a clamp block. 35 The surface of the heel 1 that is to be applied to the adjoining part of the shoe 2 is first gummed with glue and then nailed to the bottom of the shoe 2 in the manner now common.

40 When thus attached to the shoe 2, the forward edge 3 of the heel 1 underlies chamfered end 4 of the sole, as shown in Fig. 3. A last 5 is then inserted in the shoe, the said last containing a socket 6 adapted to receive the spindle 7 of the support 8 borne 45 by the cross-bar 9 carried by the corner posts 10 of a rectangular frame having rollers 11.

Cross-bar 9 bears a plurality of supports 50 8, and cross-bar 12 bears a plurality of threaded advanceable clamping bars 13, each of which supports a pivoted clamp-member 14 adapted to press against a clamp-block 15.

55 After the last 5 has been inserted in the

shoe, as shown in Fig. 3, and the same has been mounted on the support 8 by the insertion of the spindle 7 in the last socket 6, the shoe as a whole with its heel attached thereto by glue and nails occupies 60 the position depicted in Fig. 3. A clamp-block 15 is then inserted between the heel 1 and the clamp-member 14, and the crank 16 having an angular hole for coöperation with the angular head 17 of the clamp-bar 65 13 is placed in position on the said head 17, and upon the crank being revolved the screw-threaded clamp-bar 13 advances through the screw-threaded socket 18, thereby causing clamp-member 14 to bear 70 against clamp-block 15 in the manner shown in Fig. 4, in which the clamp-member 14 is shown tilted on its pivot 19 so as to present an engaging surface in alinement with the surface of block 15. Pivot 19 in 75 combination with clamp-member 14 may be (as shown in the drawings) a ball and socket arrangement. Block 15 is, also, in alinement with the sole of the shoe and the bottom of heel 1.

80 The said tilting of clamp-member 14 is provided for not only because of its pivot 19, but also by reason of the fact that the threaded clamp-bar 13 is in a vertical plane forward of the vertical plane of support 8, 85 which relative arrangement of the support 8 and the clamp-bar 13 has the additional effect of tending to seat the edge 3 of the heel 1 more tightly under or in contact with the chamfered edge 4 of the sole.

90 The application of power by crank 16 and clamp-bar 13 and clamp-member 14 to clamp-block 15 and thereby pressure to heel 1 while the glue on the top of heel 1 is still moist causes the said heel to seat firmly and 95 fixedly in its place, and the exertion of this pressure against the support afforded the rear part of the shoe by means of last 5 borne by support 8 causes the firmer connection of the heel 1 to the shoe by means 100 of the retaining nails. In brief, the hereinbefore-described operation is that of heel setting for the purpose of firmer and tighter attachment of the heel to the shoe.

105 The side view shown in Fig. 1 is substantially a duplicate of what would be shown by a view of either of the other three sides of the apparatus, which is preferably constructed rectangular in form, but if desired could be made triangular, circular, ellipti- 110

cal, or oblong, its object being to provide a frame-work on which a plurality of the individual shoe-setting clamps can be placed and on which the shoes while setting can 5 be left as long as necessary, each rack or frame as soon as filled being wheeled away to a convenient place, carrying with it its load of shoes clamped for setting, and another of the said frames or racks with its 10 individual supports empty is rolled into place for the reception of shoes requiring the heel-setting herein described.

The clamping member 14 may extend either longitudinally or laterally or both, 15 and may be of any suitable shape—circular, square, oblong, elliptical, or triangular. Preferably it will possess extension of sufficient degree frictionally to engage clamp-block 15 and to apply the desired pressure 20 to the heel as communicated therethrough to the clamp-block 15, which pressure will be communicated perpendicularly to the said clamp-block and which (depending upon the shape of the shoe) may or may not be at 25 an oblique angle to the clamp-bar 13.

Having thus described this invention, we hereby reserve the benefit of all changes in form, arrangement, order, or use of parts, as it is evident that many minor changes 30 may be made therein without departing from the spirit of this invention or the scope of the subjoined claims.

We claim:

1. A heel-setting clamp comprising in 35 combination a shoe support, a member movable toward and from the same, a clamp block of such size as to overlap both the heel and sole of the shoe, and a clamping member having swivel engagement with the 40 first-named member and arranged to bear upon the clamp block.

2. A heel-setting clamp comprising a sup-

port for a shoe, a longitudinally-movable compression member, a clamping member, and a freely removable clamping block of 45 such size as to rest upon both the heel and toe of the shoe and disposed in the path of movement of the clamping member.

3. A heel-setting clamp comprising a support for a shoe, a threaded advanceable compression member, a clamping member mounted for universal movement on the end of the said compression member, and a clamping block of such size as to engage both 50 the heel and the toe of a shoe and disposed in the path of movement of the clamping member.

4. A heel-setting clamp comprising a support for a shoe, a vertically-disposed screw-threaded clamp bar disposed above and in 60 advance of said support, a clamping member, a ball and socket connection between the clamp bar and clamping member, and a clamp block of such size as to rest upon 65 both the heel and the sole of the shoe and disposed in the path of movement of the clamping member.

5. In a heel-setting clamp the combination with a support for a shoe of a rigid element disposed thereabove, a clamp bar 70 threaded for vertical movement therein, a clamp block of such size as to rest upon both the heel and toe of the shoe, and a clamp member adapted to engage said bar to clamp the same upon the shoe, said 75 clamp member being capable of movement to varying angles with respect to the clamp bar during the clamping operation.

In testimony whereof we hereunto affix 80 our signatures.

GEORGE W. JULOW.
DAVID E. SPATHELF.
EUGENE SEHL.
